UNITED STATES PATENT OFFICE.

EDWARD SENN, OF BIRMINGHAM, ALABAMA, ASSIGNOR TO SENN PRESSED STEEL HOE AND TOOL COMPANY, OF BIRMINGHAM, ALABAMA, A CORPORATION OF ALABAMA.

HOE

1,129,052.

Specification of Letters Patent. Patented Feb. 16, 1915.

Application filed August 25, 1913. Serial No. 736,528.

To all whom it may concern:

Be it known that I, EDWARD SENN, a citizen of the United States of America, residing at Birmingham, in the county of Jefferson and State of Alabama, have invented 5 certain new and useful Improvements in Hoes, of which the following is a specification.

My invention relates to improvements in 10 hoes and has for its object to improve the hoe which is described in Letters Patent No. 922,202, issued to me on the 18th day of May, 1909.

One object of my invention is to 15 strengthen the neck of the hoe, which connects the blade and socket portion, by a corrugation which extends along the vertical center line of the neck and merges into the blade and socket portions of the hoe blank 20 at points spaced from the neck.

A further object of my invention is to 25 strengthen the neck by tapering the inner ends of the notches or slots on each side of the neck to increase the amount of metal available at that point to be bent or folded inwardly about the corrugated neck portion to reinforce it.

A further object is to compress the double 30 thickness of metal forming the reinforced sides of the neck, forcing all parts inwardly from each side of the neck at its center.

My invention further comprises the novel 35 details of construction and arrangements of parts which in their preferred embodiment only, are hereinafter more particularly described and claimed, and which are illustrated in the accompanying drawings forming a part of this specification, and in which:

40 Figure 1 is a plan view of the hoe blank. Fig. 2 shows the blank with the reinforcing corrugation impressed therein and the socket partly formed. Fig. 3 is a front elevation of the finished hoe. Fig. 4 is a side elevation of the hoe. Fig. 5 is a rear elevation of the hoe. Figs. 6 and 7 are cross sectional views through the neck of the hoe taken on the lines $x-x$ and $y-y$, respectively, of Fig. 4. Figs. 8, 9 and 10 are views corresponding to Figs. 1, 2 and 3, and illustrate a double hoe made in accordance with my present invention.

Similar reference numerals refer to similar parts throughout the drawings.

55 The hoe, according to my present inven-

tion, is formed from the blank shown in Fig. 1, and which comprises the blade 1 and a neck portion 2 which connects the socket portion 3 to the blade. It will be noted that the inner ends of the slots 4, which space 60 wings 5 on the socket portion from the blade, are not rounded, as in the case of my former patent, but are tapered to a point in the plane of the top line of the blade, thereby providing excess metal 6 which strengthens the neck. 65

A corrugation or rib 7 is formed by indenting the rear face of the hoe blank, the corrugation starting in gradually in the upper central portion of the blade 1 and continuing along a vertical center line across the neck 2 and terminating in a widened rounded depression which disappears about the middle of the socket portion 3. Where this corrugation crosses the neck proper it 70 extends practically across the whole neck so that the cross section of the neck, where it joins the blade, is substantially V-shaped. When the blank is thus corrugated, the two 75 wings 5 are bent rearwardly into substantial parallelism and the socket portion 3 is bent at the desired angle to the blade. The socket is next formed by dies which curve the wings in transverse cross section and squeeze the top edges of the wings together 80 which causes the center of the section 3 at its top to be creased at 8 to bring its edges on each side of the vertical center line together. The metal portions 6 of the neck are given 85 a twist and folded inwardly against the adjacent sides of the V-shaped neck and the neck is then slightly crimped by forcing the overlapping folds of metal forming the reinforced neck inwardly from each side which 90 gives a compact, rigid and short neck that 95 is amply strong enough for the hoe. By the neck I mean that portion of the blank which serves as a connection between the blade and socket portions and such neck being formed between the lateral slots 4 100 with their inner ends tapered by a slightly curved top line as shown or by a straight line at an acute angle to the top line of the blade, or such slots may be cut with their side walls approaching at any desired curve 105 or angle but I prefer to have the slots leave sufficient metal at the points 6 so that it can be folded over and crimped against the corrugated neck to give it the maximum 110 strength to withstand all strains on it.

In Figs. 8, 9 and 10, a double ended hoe or tool is shown, the blank here providing a central socket portion 10 connected by neck portions 11 to differently shaped blades 12 5 and 13. The socket portion has wings 5, as in the case of Fig. 1, and these wings are shaped and twisted to form a socket. The corrugation 14 for strengthening the neck extends entirely across the socket portion 3 10 and necks 11 into the blade portions.

The wings 5 are perforated to receive screws or rivets 15 by means of which the hoe is fastened to the handle 16. Other fastening means may, however, be employed.

15 My invention is equally applicable to the manufacture of tools similar to hoes and my claims are intended to apply generally to such tools.

What I claim as new and desire to secure 20 by Letters Patent, is:—

1. As an article of manufacture, a hoe comprising a blade, socket portion and a relatively narrow portion connecting the blade and socket portion, all formed from 25 a blank which has a vertical corrugation extending from the blade across the connecting portion into said socket portion, the sides of said narrow portion of the blank adjoining the socket portion being twisted 30 to engage and reinforce the corrugated connecting portion.

2. As an article of manufacture, a hoe formed from a blank comprising blade and socket portions connected by a relatively 35 narrow corrugated neck, said neck increasing in width toward the socket portion to provide side portions thereof adapted to be bent inwardly on each side against the convex wall of the neck to reinforce it, sub- 40 stantially as described.

3. As an article of manufacture, a hoe formed from an integral blank having blade and socket portions connected at their centers and spaced at their sides by lateral slots, 45 said blank being indented to form a corrugation which extends part way into each of said portions and continues across the metal connecting said portions, giving it substantially a V-shaped horizontal cross section, 50 and wings on the socket portion which are shaped and twisted to form between them a socket and which have each a portion that is folded over and pressed against the expressed walls of said V-shaped connecting

portion to reinforce it, substantially as de- 55 scribed.

4. As an article of manufacture, a hoe or like tool formed entirely of pressed metal, the hoe comprising a blade, a socket portion and a relatively narrow neck portion connecting said blade and socket portion and formed by slots which lead inwardly from opposite points in the sides and taper at their inner ends, a corrugation which extends from the blade vertically and centrally 60 across the neck into the socket portion, and portions of the metal in the socket portion which are adapted to be bent together to form a socket and pressed against the offset walls of the indented neck to reinforce it, 65 substantially as described.

5. As an article of manufacture, a hoe or like tool formed entirely of pressed metal, the hoe comprising a blade, a socket portion and a relatively narrow neck portion connecting said blade and socket portion and formed by slots which lead inwardly from opposite points in the sides and taper at their inner ends, a corrugation which extends from the blade vertically and centrally 70 across the neck into the socket portion, and reinforcing portions of metal left near the juncture of the neck and socket portions which are bent inwardly over and crimped against the expressed sides of the 75 corrugated neck to reinforce it.

6. A hoe comprising a blade and a socket portion formed from a blank which has lateral slots cut from opposite points inwardly to points near the vertical center line of the hoe, said slots having their inner walls cut at an incline to leave between them a neck portion which flares from the top line of the blade to the point of juncture 90 with the socket portion to provide excess metal to reinforce the neck, a corrugation which extends centrally across said neck portion, the sides of the socket portion being bent and shaped to form the socket and said excess metal of the neck being folded against 95 the convex sides of said corrugation to reinforce it, substantially as described.

In testimony whereof I affix my signature in presence of two witnesses.

EDWARD SENN.
